Primary Examiner — Paula Allen Greene

(57) **CLAIM**

The ornamental design for an electronic hearing protector, as shown and described.

DESCRIPTION

FIG. 1 is a top perspective view of an electronic hearing protector showing my new design;

FIG. 2 is a bottom perspective view thereof;

FIG. 3 is a front view thereof;

FIG. 4 is a rearview thereof;

FIG. 5 is a left view thereof;

FIG. 6 is a right view thereof;

FIG. 7 is a top view thereof; and,

FIG. 8 is a bottom view thereof.

The broken lines depict portions of the electronic hearing protector form no part of the claimed design.
